FIG. 1 is a perspective view of a hammer for shredding machines in accordance with the present invention; FIG. 2 is a front view thereof;

FIG. 3 is a top view thereof;

FIG. 4 is a first side view thereof;

FIG. 5 is a back view thereof;

FIG. 6 is a second side view thereof; and,

FIG. 7 is a bottom view thereof.

The broken lines immediately adjacent the shaded areas and define unshaded regions represent the bounds of the claimed design while all other broken lines are directed to environment; the broken lines form no part of the claimed design.
